UNITED STATES PATENT OFFICE

144,130

DESIGN FOR A SUBSTATION TELEPHONE INSTRUMENT

Herbert F. Obergfell, deceased, late of River Forest, Ill., by Amanda Obergfell, executrix, River Forest, Ill., assignor to Automatic Electric Laboratories, Inc., Chicago, Ill., a corporation of Delaware

Application January 1, 1945, Serial No. 117,216

Term of patent 14 years

(Cl. D26—14)

To all whom it may concern:

Be it known that Herbert F. Obergfell, deceased, late a citizen of the United States of America and a resident of River Forest, Cook County, Illinois, has invented a new, original, and ornamental Design for a Substation Telephone Instrument, of which the following is a specification, reference being had to the accompanying drawing, forming a part thereof, in which:

Figure 1 is a front perspective view of the sub-

station telephone instrument of the new design.

Figure 2 is a rear perspective view of the same instrument.

The dominant features of my design reside in the portions shown in full lines.

I claim:

The ornamental design for a substation telephone instrument, as shown and described.

AMANDA OBERGFELL,
*Executrix of the Estate of Herbert F. Obergfell,
Deceased.*
